UNITED STATES PATENT OFFICE.

GEORGE F. SISBOWER, OF EAST ORANGE, NEW JERSEY, AND LOUIS EDWARD PITTONI, OF NEW YORK, N. Y., ASSIGNEES TO NEW YORK COUCH BED COMPANY, OF NEW YORK, N. Y., A CORPORATION OF NEW YORK.

BED-SPRING.

1,138,986.

Specification of Letters Patent. Patented May 11, 1915.

Application filed November 4, 1912. Serial No. 729,478.

To all whom it may concern:

Be it known that we, GEORGE F. SISBOWER, a citizen of the United States, residing at East Orange, in the county of Essex and State of New Jersey, and LOUIS EDWARD PITTONI, a subject of the King of Italy, residing at New York city, county and State of New York, have invented certain new and useful Improvements in Bed-Springs, the following being a full, clear, and exact disclosure of the one form of our invention which we at present deem preferable.

For a detailed description of the present form of our invention, reference may be had to the following specification and to the accompanying drawing forming a part thereof, in which—

Figure 1 is a plan view partly in section of a portion of a bed-spring fabric provided with our improvement. Fig. 2 is a vertical section through the edge of the fabric. Figs. 3, 4 and 5 show modifications.

Our invention relates to bed springs of the type formed by a metallic mattress fabric adapted to be stretched under spring tension on a rigid frame. It involves a device for reinforcing the edge of the fabric and securing it to the end springs which ordinarily intervene between the fabric and the frame on which it is stretched.

Referring to the drawing, A represents the metallic fabric, preferably what is known as a "woven wire" fabric, and B represents one side of the frame on which the fabric is to be stretched. Between the fabric A and the frame-bar B are series of coiled springs C, C, etc., such as are ordinarily interposed at that point to give resiliency to the structure, one end of each spring being hooked into the frame-bar and the other end secured to the fabric. The edge of the fabric, in our arrangement, is secured directly to a metallic piece D which we term a core piece or core bar, the fabric being preferably folded around it. The said core piece is shown in Figs. 1 and 2 in the form of a metal rod or bar with extensions F, F, etc. thereon at intervals. These extensions project away from the edge of the fabric toward the frame-bar B and are perforated for receiving the end-springs C, C which are hooked into the perforations. In Fig. 5 the core piece D is in the form of a round rod or wire with the extensions F produced by bending

the rod or wire into loops. In Figs. 3 and 4 the core piece D is in the form of a plain flat bar without the extensions but perforated at intervals for the reception of the end springs which engage it. The fabric itself is also perforated correspondingly, by the pushing aside of the wires of which it is woven, so that the extensions F may project through the fabric, or the hooks of the end springs may pass through the fabric when the core piece is of the form shown in Figs. 3 and 4. Outside of the core piece D is placed a metallic U-shaped cover plate E which is also perforated at intervals to receive the extensions F or the hooks of the end springs, in the form shown in Figs. 3 and 4. This cover plate embraces between its upper and lower portions the core piece and also the edge of the fabric, being bent down thereon under heavy pressure. The internal space within the cover plate is larger where it embraces the core piece and fabric, and is smaller outside the core piece where it merely embraces and pinches down on the fabric itself. By this means the cover plate is secured in place by virtue of its grip on the core piece, while by having the folded edge of the fabric gripped or pinched in the smaller portion of the internal space within the cover plate the fabric is more securely held against detachment from the core piece.

Among the advantages of our arrangement is the fact that it is far cheaper to construct than the one now commonly employed, wherein separate metallic strips are riveted above and below the edge of the fabric, besides which, it gives a more attractive and neater finish to the fabric and provides a more convenient attachment of the end spring hooks and is more secure while preventing at the same time the spreading and fraying of the fabric.

What we claim as new and desire to secure by Letters Patent is:

1. A woven-wire mattress-fabric having its edge inclosed by a cover-plate carried by the fabric, the said cover-plate containing a core piece over which the fabric is turned, and retained by the cover-plate, the said core piece being adapted for the engagement of spring-hooks therewith and the cover-plate being perforated at intervals to permit such engagement of the hooks and core-piece,

2. A woven-wire mattress-fabric having its edge inclosed by a cover-plate carried by the fabric, the said cover-plate containing a core piece over which the fabric is turned and retained by the cover-plate, the said core-piece having perforated extensions projecting therefrom laterally through openings in the cover-plate, for the engagement of spring-hooks with the core-piece.
- 5 10 3. A woven-wire mattress-fabric having its edge inclosed by a flat cover-plate carried by the fabric and perforated at intervals, the said cover-plate being bent over the fabric edge and containing a core-piece around which the fabric is folded and pressed into engagement with the fabric at one side of the core to grip and retain in place the folded fabric.
- 15 20 4. A woven-wire mattress-fabric having its edge inclosed by a cover-plate independent of the end rail of the frame and bent into a horizontal U-shape, a core-piece adapted to be engaged by the attaching spring hooks and having the fabric bent over it and retained by the cover-plate being pressed into engagement with the fabric at one side of the core, and the said cover-plate being perforated at intervals to permit of the said engagement of the core-piece
- 25 30 5. A woven-wire mattress-fabric having its edge inclosed by a cover-plate secured thereto independently of the end rail of the mattress frame and perforated at intervals, a core-piece within said cover-plate over
- 35 which the edge of the fabric is turned and loops or eyes projecting through said perforations in the cover-plate.
6. A woven-wire mattress-fabric having a folded plate inclosing the edge of the mattress, and a retaining core-piece also inclosed by said plate and provided with a series of loops or eyes projecting through a corresponding series of openings in the plate.
- 40 45 7. A woven-wire mattress-fabric having a folded plate independent of the mattress-frame inclosing the edge of the mattress, and a retaining core-piece also inclosed by said plate, the core-piece and the plate both having a series of corresponding perforations and the core-piece being secured to the fabric by the grip of the said plate thereon.
- 50 55 8. A woven-wire mattress-fabric having a flat folded plate independent of the mattress frame, and a retaining core-plate separate from the mattress frame inclosed by said edge-plate, both plates having a corresponding series of hook holes for attaching the springs and the folded plate having flat clamping extensions gripping the fabric inside of the core-plate.

In witness whereof we have hereunto set our hands, before two subscribing witnesses, this first day of November 1912.

GEORGE F. SISBOWER.
LOUIS EDWARD PITTONI.
